UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 5, 1923. Serial No. 636,769.

My invention relates to railway traffic controlling apparatus of the type comprising train carried governing means controlled by energy received from the trackway.

5 I will show one form of apparatus embodying my invention and one modification thereof, and will then point out the novel features thereof in claims.

In the accompanying drawings, Fig. 1 is 10 a diagrammatic view showing one arrangement of apparatus embodying my invention as applied to a portion of railway track over which traffic moves in one direction only. Fig. 2 is a view showing one modification 15 of the arrangement shown in Fig. 1 and also embodying my invention. The apparatus shown in Fig. 2 is adapted for use on a single track railway over which traffic normally moves in both directions.

20 Similar reference characters refer to similar parts in both views.

Referring particularly to Fig. 1, the reference characters 4 and 4^a designate the track rails of a railway over which traffic 25 normally moves in the direction indicated by the arrow. These rails are divided, by means of insulated joints 3, into a plurality of consecutive track sections, only one of which, A—B, is shown in the drawing. 30 Each track section is provided with a source of track circuit current. As shown in the drawing, the immediate source of such current is a track transformer designated by the reference character T with an exponent corresponding to the location and having its 35 secondary winding 5 connected across the rails adjacent the exit end of the section. Interposed between one rail 4 of each section and the secondary 5 of the associated track 40 transformer T is an impedance 6 one function of which is to limit the output of the transformer when its terminals are short-circuited by the wheels and axles of a passing train. The primary 7 of each track 45 transformer T is constantly supplied with alternating current from some suitable source such as a generator G over line wires 11 and 11^a.

Each track section is further provided 50 with a track relay which is connected across the rails adjacent the entrance end of the section and is designated by the reference character R with an exponent corresponding to the location.

It is therefore clear that each track section is provided with a track circuit including a secondary 5 of a track transformer T, an impedance 6, a track relay R, and the rails 4 and 4^a of the section in series.

Means are also provided for supplying to 60 the rails in parallel of section A—B a current which I will hereafter term a "local current". The immediate source of this current is a double-secondary local transformer K^a whose primary 8 is constantly supplied with alternating current from generator G over line wires 11 and 11^a. The section is also provided with an impedance 12 connected across the rails adjacent the exit end of the section, a similar impedance 15 connected across the rails adjacent the entrance end of the section, and two similar impedances 13 and 14 connected across the rails at an intermediate point in the section.

Before proceeding further with the description it should be pointed out that the trackway apparatus herein shown and described is intended for co-operation with train-carried governing apparatus in the following manner: When the train is on a portion of track which is supplied with track circuit current and with local current of normal relative polarity the governing apparatus displays a proceed indication which allows the train to proceed at a high speed 75 such as 65 miles per hour; if the train occupies a portion of track which is supplied with track circuit current and with local current of reverse relative polarity, the governing mechanism presents a caution aspect 80 which prevents the train from exceeding an intermediate speed such as 35 miles per hour, while if the train enters a portion of track to which the supply of either track circuit current or local current is for any 85 reason interrupted, the governing mechanism displays a stop indication which prevents the train from exceeding a low speed 90 such as 15 miles per hour.

Referring again to Fig. 1, the section A—B contains a permanent hazard extending between those points in the section indicated by the reference characters 1 and 2. The hazard may be a curve, a bridge, a tunnel, or any similar topographical feature 105 which always requires that to insure safety a restricted train speed must be maintained through this portion of track.

In my invention I arrange the circuits for the local current in such a way that this speed reduction will be effective upon a vehicle automatically.

5 It will be noted that impedances 13 and 14 in section A—B are located adjacent the left hand end of this hazard 1—2. Section A—B is provided with one local circuit which passes from secondary 9 of local transformer K^A through wire 20, impedance 14 in section A—B, through both rails of the section in parallel to impedance 15, thence by wire 21 back to secondary 9 of transformer K^A . This circuit is always closed and local current of reverse relative polarity is therefore constantly supplied to the rails of section A—B between impedances 14 and 15. Another local circuit passes from secondary 10 of transformer K^A through wire 16, impedance 13 in section A—B, through both rails of the section in parallel to impedance 12, thence through wire 19, front contact 18 of track relay R^A , and wire 17 back to secondary 10 of transformer K^A . This circuit is closed only when relay R^A is energized under which condition local current of normal relative polarity is supplied to the rails of section A—B between impedances 12 and 13. If, however, relay R^A is deenergized, as 20 by the presence of a train in the section to the left of A, this circuit is interrupted and no local current is supplied to the rails of section A—B between impedances 12 and 13.

I will now assume that section A—B is 35 unoccupied, and that a train moving in the direction of the arrow enters section A—B at point B. The governing apparatus is supplied with track circuit current from track transformer T^A , and with local current of 40 reverse relative polarity from secondary 9 of local transformer K^A . The speed of the train is therefore restricted to 35 miles per hour until it has passed the left hand extremity 1 of the hazard 1—2. If the section to the left of A is unoccupied, the supply of local current of normal relative polarity commencing at impedance 13 will allow the train to accelerate to 65 miles per hour, but if the section to the left of point A is occupied, the 45 train speed is immediately reduced to 15 miles per hour by the interruption of the local circuit. It is plain therefore that a constant speed restriction is imposed upon a train while passing the hazard, irrespective of traffic conditions, and that the speed of the train is further controlled, in response to traffic conditions, after the hazard has been passed.

55 Referring now to Fig. 2, in which I have shown my invention applied to a single track railway over which traffic moves in both directions, the track rails 4 and 4^a are divided as before into a plurality of successive track sections A—B, B—C, etc.

60 Each end of each track section is provided

with a track transformer designated in general by the reference character T and specifically by a suitable exponent and having its secondary 5 constantly connected with the rails of the associated section through an 70 impedance 6. The energization of the primary 7 of these track transformers will be explained in detail hereinafter. Each track section is also provided with two track relays, one located at each end, and designated 75 by the reference character R with a suitable exponent. Associated with each track relay R is a "line" relay and a "stick" relay designated by the reference characters H and S , respectively, with suitable distinguishing 80 exponents.

Each section is also provided with a repeater relay designated by the reference character P with a suitable exponent and located adjacent the left hand end of the 85 section.

Each track relay R is provided with two windings 27 and 28, one of which, 28, is constantly connected with a source of alternating current. Thus, referring particularly to relay R^3 , a circuit is provided which passes from the secondary of a transformer D^B , whose primary is constantly supplied with alternating current from generator G over line wires 11 and 11^a , through wire 31, 90 winding 28 of track relay R^3 , and wires 32 and 30 back to transformer D^B . Another circuit is provided for this relay passing from rail 4 of section B—C through wire 33, winding 27 of relay R^3 , wire 34, back contact 35 of relay P^3 , and wire 36 back to rail 4 a of section B—C. It is clear that this circuit is closed only when relay P^3 is de-energized under which conditions relay R^3 is 95 connected across the rails of section B—C. The track relay located adjacent the left hand end of each of the remaining sections is similarly controlled by the associated repeater relay P . The relay R located at the right hand end of each section is constantly 100 connected with the rails of the section through an impedance 29 the function of which will appear hereinafter. Means are provided for at times closing a low resistance shunt around this impedance. Thus referring particularly to relay R^2 a shunt path 105 passes from the right hand side of impedance 29, through wire 37, front contact 38 of stick relay S^2 , and wire 39 back to the left hand side of impedance 29. This low resistance 110 shunt is closed only when relay S^2 is energized, under which condition impedance 29 is shunted out of the circuit for relay R^2 .

The track transformer located at the left hand end of each section is normally disconnected from its source of energy. Referring particularly to transformer T^3 , a circuit is provided passing from transformer D^B through wires 31 and 40, front contact 41 of repeater relay P^3 , wire 42, primary winding 120

7 of track transformer T^3 , and wire 30 back to transformer D^3 . This circuit is closed only when relay P^3 is energized, under which condition track circuit current will be supplied to section B-C from transformer T^3 . Track transformer T^2 located at the right hand end of section B-C is provided with a circuit which passes from transformer D^2 through wires 43 and 44, back contact 45 of stick relay S^2 , wire 46, primary winding 7 of track transformer T^2 , and wire 30 back to transformer D^2 . This circuit is closed only when relay S^2 is deenergized, under which condition track circuit current is supplied to the rails of section B-C from track transformer T^2 . It will be clear from the foregoing that at times a source of energy is connected directly across the terminals of relay R^2 and for this reason the impedance 29 is necessary to protect the winding 27 from excessive current. But when the track circuit is being fed from the remote end, this current limiting impedance is unnecessary and undesirable and hence means are provided for establishing a path of low resistance around this impedance as already explained.

Line relay H^3 is provided with a circuit passing from transformer D^3 through wires 30 43 and 47, front contact 48 of line relay H^3 , wire 49, front contact 50 of relay R^2 , wire 51, back contact 52 of stick relay S^4 , wire 53, front contact 54 of track relay R^3 , wire 55, winding of relay H^3 , and wires 56 and 30 back to transformer D^3 . When stick relay S^4 is deenergized and relays R^3 , R^2 and H^3 are all energized, the circuit just traced is closed, thus energizing relay H^3 . This circuit is provided with a branch passing from wire 43, through wire 57, front contact 58 of stick relay S^5 and wire 59 back to wire 49. The circuit is closed through this branch only when stick relay S^5 is energized, under which condition relay H^3 is moved from the control of relay H^3 . The remaining line relays H are controlled over circuits exactly similar to that just described for relay H^3 .

Each stick relay S is controlled by its associated line relay H and the adjacent track relays R as follows: Referring particularly to relay S^2 , a pick-up circuit passes from transformer D^2 through wires 43 and 60, back contact 61 of line relay H^5 , wire 62, back contact 63 of track relay R^2 , wire 64, back contact 65 of track relay R^2 , wire 66, front contact 67 of line relay H^2 , wire 68, winding of relay S^2 , and wires 69 and 30 back to transformer D^2 . It is clear, therefore, that since a train moving from right to left into section B-C will de-energize track relays R^2 and R^5 simultaneously and since relay H^5 is already de-energized, the circuit just traced will be closed, thus energizing the stick relay S^2 . The de-energization

of the track relay R^2 de-energizes line relay H^5 but before this relay has time to open its front contacts, stick relay S^2 closes its front contact, and even though the pick-up circuit for S^2 is broken at front contact 67 of relay H^5 , relay S^2 is held closed by a stick circuit which passes from transformer D^2 through wires 43 and 70, back contact 71 of track relay R^2 , wire 72, front contact 73 of stick relay S^2 , wire 74, winding of relay S^2 , and wires 69 and 30 back to transformer D^2 .

Each repeater relay P is arranged to be energized only when the stick relay at the other end of the associated section is energized. Referring particularly to relay P^3 the circuit for this relay passes from transformer D^3 through wires 43 and 75, front contact 76 of relay S^2 , wire 77, back contact 78 of track relay R^2 , wire 79, back contact 80 of relay S^5 , wire 81, back contact 82 of relay R^3 , wire 83, winding of repeater relay P^3 , and wires 84 and 30 back to transformer D^3 . It is clear that this circuit is closed and relay P^3 is energized only when relay S^2 is energized and relays R^3 , R^2 and S^5 are de-energized.

It will be observed that section A-B contains, as in Fig. 1, a permanent hazard 1-2, whereas, no such hazard is found in section B-C.

Section B-C is provided with a local circuit which passes from secondary 9 of local transformer K^C , through wire 85, front contact 86 of relay H^5 , wires 87 and 88, impedance 15 in section B-C, thence through both rails of the section in parallel to impedance 12, wire 89, back contact 90 of relay P^3 , wire 91, back contact 92 of relay S^2 , wire 93, front contact 94 of relay H^5 , and wire 95 back to secondary 9 of local transformer K^C . This circuit is closed only when relays S^2 and P^3 are de-energized and relay H^5 is energized under which condition the rails of section B-C are supplied with local current of normal relative polarity throughout their length. If, however, relay H^5 is de-energized, as by a train moving toward the right and occupying the section to the right of C, a local circuit is closed allowing current to flow from secondary 9 of local transformer K^C through wire 85, back contact 86 of relay H^5 , wire 93, back contact 92 of stick relay S^2 , wire 91, back contact 90 of repeater relay P^3 , wire 89, impedance 12 in section B-C, through both rails of the section in parallel to impedance 14, thence through wire 96, back contact 94 of relay H^5 , and wire 95, back to secondary 9 of transformer K^C . The closing of this circuit supplies the rails of section B-C with local current of reverse relative polarity between the left hand end of the section and impedance 14, but with no local current from impedance 14 to the right hand end of the section. For traffic moving from right to

left, local current is supplied in a similar manner by secondary 10 of transformer K^B , the only difference being that wire 91 is now connected to the front instead of the back contacts of relays S^2 and P^3 . Similar local circuits are also provided for the partial sections to the left of point A and to the right of point C, respectively. It is understood, of course, that impedances 13 and 14 are located at sufficient distances from the associated ends of the sections, respectively, to permit the train to be reduced from 35 miles per hour to a final stop between impedances 13 and 12 or between impedances 14 and 15, depending on the direction of traffic.

Assuming that the hazard in section A—B is so located that its left hand extremity is adjacent to impedance 13 and its right hand extremity is some distance to the left of impedance 14, the local circuits are arranged as follows: In addition to the four impedances 12, 13, 14 and 15 similar to those with which section B—C is provided, section A—B is provided with an impedance 22 connected across the rails adjacent impedance 13 and two impedances 23 and 24 connected across the rails of the section and located at the right hand extremity of the hazard 1—2. An auxiliary local transformer is also provided for each end of this section and designated by the reference character L with an exponent corresponding to the location.

Section A—B is provided with a local circuit which passes from secondary 10 of transformer K^A , through wire 105, impedance 22 in section A—B, through both rails in parallel, to impedance 23, and wire 106 back to secondary 10 of transformer K^A . The circuit is closed at all times and local current of reverse relative polarity is therefore constantly supplied to section A—B between impedances 22 and 23. Traffic moving from left to right through section A—B is supplied with local currents over circuits as follows: One circuit passes from secondary 26 of local transformer L^A , through wire 100, impedance 12 in section A—B, through both rails of the section in parallel to impedance 13, thence through wire 99, back contact 98 of repeater relay P' , and wire 104 back to secondary 26 of transformer L^A . This circuit is closed only when relay P' is de-energized, under which conditions local current of reverse relative polarity is supplied to the rails of section A—B between impedances 12 and 13. Another local circuit is provided passing from secondary 9 of local transformer K^B , through wire 110, front contact 111 of relay H^3 , wires 112 and 109, impedance 15 in section A—B, through both rails of the section in parallel to impedance 24, wire 117, back contact 108 of relay S^4 , wire 113, front contact 114 of

relay H^3 , and wire 115 back to secondary 9 of transformer K^B . When this circuit is closed, local current of normal relative polarity is supplied to the rails of section A—B between impedances 24 and 15. If, however, relay H^3 is de-energized, as by a train moving from left to right and occupying section B—C, a local circuit is closed which passes from secondary 9 of local transformer K^B , through wire 110, back contact 111 of relay H^3 , wire 113, back contact 108 of relay S^4 , wire 117, impedance 24 in section A—B, through both rails of the section in parallel to impedance 14, wire 116, back contact 114 of relay H^3 and wire 115 back to secondary 9 of transformer K^B . When this circuit is closed the rails of the section are provided with local current of reverse relative polarity between impedances 24 and 14 but with no local current between impedances 14 and 15.

A train moving from right to left through section A—B will energize relays S^4 and P^3 as explained hereinbefore and thereby close a circuit from secondary 25 of local transformer L^B , through wire 107, front contact 108 of relay S^4 , wire 117, impedance 24 in section A—B, through both rails of the section to impedance 15, thence through wire 109 back to secondary 25 of transformer L^B . This circuit is closed only when relay S^4 is energized under which condition transformer L^B supplies local current of reverse relative polarity to the rails of section A—B between impedances 24 and 15. Another circuit is provided for traffic moving from right to left, this circuit passing from secondary 25 of transformer L^A , through wire 97, front contact 98 of relay P' , wire 99, impedance 13 in section A—B, thence through both rails in parallel of the section to impedance 12, wires 100 and 101, front contact 102 of relay H^6 , and wire 103 back to secondary 25 of transformer L^A . Local current of normal relative polarity is supplied to the rails of section A—B between impedances 12 and 13 over the circuit just traced, only when relays H^6 and P' are energized.

In explaining the operation of the apparatus as a whole I will assume that a train moving from left to right enters the stretch of track shown in the drawing. This train will be allowed to proceed at 65 miles per hour as far as point A, where the reversal of the local current will cause the governing mechanism to impose an intermediate speed limitation, thus reducing the train speed to 35 miles per hour. This restriction continues throughout the hazard or as far as impedance 24 in section A—B where the local current is again reversed, thus allowing the train to accelerate to 65 miles per hour and proceed at high speed through the rest of section A—B and section B—C. If, however, section B—C is occupied by a train moving

from left to right, relay H^3 will be de-energized and the intermediate speed restriction will continue as far as impedance 14, where the cessation of the local current will cause the train speed to be still further reduced to 15 miles per hour. If section B-C is unoccupied but the section to the right of C is occupied by a train moving toward the right, the train in section A-B will be allowed to accelerate as before but the intermediate speed restriction will be imposed as the train enters section B-C and the low speed restriction will be established as the train passes impedance 14 in section B-C.

For traffic moving from right to left through section B-C, the operation of the apparatus associated with the section will be readily understood from the foregoing. A train moving from right to left and entering section A-B is, however, immediately restricted to 35 miles per hour if not already below that speed and this restriction is maintained till the train has passed impedance 13. If the section to the left of A is unoccupied, the local current is reversed at point 13 and the train is allowed to accelerate, but if a train moving from right to left occupies the section to the left of point A the consequent de-energization of relay H^6 interrupts the local circuit for section A-B between impedances 12 and 13 and the consequent discontinuance of local current in this portion of track causes a low speed limitation to be imposed upon the train which is then allowed to proceed only at speeds not in excess of 15 miles per hour.

The operation of the apparatus associated with the section to the left of point A is similar in all respects to the apparatus associated with section B-C and will be understood from the foregoing without further explanation.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In an automatic train control system comprising a trackway, including a portion of track containing a permanent hazard, means for constantly supplying the rails of said portion in parallel with alternating current of one relative polarity only, and means for supplying alternating current of one relative polarity or the other to the rails in parallel of the remaining portions of such trackway.

2. In an automatic train control system comprising a trackway, including a portion of track containing a permanent hazard,

means independent of traffic conditions for supplying current of one relative polarity to the rails of said portion in parallel, and means responsive to traffic conditions for at times supplying current of the other relative polarity to the rails in parallel adjacent said portion.

3. An automatic train control system comprising a section of railway track comprising three adjoining portions the central one of which portions contains a permanent hazard, means for constantly supplying said central portion with local current of one relative polarity, means responsive to traffic direction and conditions for at times supplying one end portion with local current of said one relative polarity and at other times for supplying said one end portion either with local current of the other relative polarity or with no local current, and means for supplying local current of said one relative polarity throughout the length of the remaining portion of such section, or for supplying local current of the other relative polarity to the last-mentioned portion throughout its length or for a part only of the said portion, depending upon the direction in which traffic occupying the section is moving.

4. In combination, a section of railway track adapted to accommodate traffic moving in two directions and comprising a portion of track adjacent the center of said section containing a permanent hazard, means for constantly supplying said central portion of track with current of one relative polarity, and means for each of the remaining portions of said section and effective only when such portion is occupied by a train moving toward said central portion for supplying the portion of track with current of said one relative polarity.

5. In combination, a section of railway track adapted to accommodate traffic moving in two directions and comprising a portion of track adjacent the center of said section containing a permanent hazard, means for constantly supplying said central portion of track with current of one relative polarity, and means for supplying each of the remaining portions of said section with current of said one relative polarity when such portion is occupied by a train moving toward said central portion or for at times supplying each such remaining portion with current of the other relative polarity when such portion is occupied by a train moving away from said central portion.

6. In combination, a section of railway track adapted to accommodate traffic moving in two directions and comprising three adjoining portions of track the central portion containing a permanent hazard, means for constantly supplying said central portion with current of one relative polarity, means

- for each of the remaining portions of said section and operative only when such portion is occupied by a train moving toward said hazard for supplying the portion with current of said one relative polarity, means for one of said last-mentioned portions and operative only when such portion is occupied by a train moving away from the hazard for supplying the portion with current of the other relative polarity or for interrupting said supply in accordance with traffic conditions, and means for the remaining last-mentioned portion and operative only when such portion is occupied by a train moving away from the hazard for supplying the portion with current of the said given relative polarity through a part of said portion or with current of the other relative polarity throughout the length of the portion, depending on traffic conditions.
7. In combination, a section of railway track comprising three adjoining portions

the central one of which contains a permanent hazard, means for constantly supplying said central portion with local current, and means responsive to traffic conditions for supplying the remaining portions of said section with local current when such portions are occupied by traffic moving away from said hazard.

8. In combination, a section of railway track comprising three adjoining portions the central one of which contains a permanent hazard, means for constantly supplying said central portion with local current of one relative polarity, and separate means for at times supplying each of the remaining portions of such section with local current of said one relative polarity or the other relative polarity in accordance with traffic conditions.

In testimony whereof I affix my signature.

RONALD A. McCANN.
